CLAIM

The ornamental design for a desk lamp, as shown and described.

DESCRIPTION

FIG. 1 is a perspective view of a desk lamp design showing my new design.

FIG. 2 is a front view of the desk lamp.

FIG. 3 is a rear view of the desk lamp.

FIG. 4 is a left side view of the desk lamp.

FIG. 5 is a right side view of the desk lamp.

FIG. 6 is a top view of the desk lamp; and,

FIG. 7 is a bottom view of the desk lamp.

The broken lines shown in the drawings illustrate portions of the desk lamp and form no part of the claimed design.
